CARLTON W. BROWN, OF GROTON, CONNECTICUT.

TAG.

1,244,832.

Specification of Letters Patent. Patented Oct. 30, 1917.

Application filed February 14, 1916. Serial No. 78,265.

To all whom it may concern:

Be it known that I, CARLTON W. BROWN, a citizen of the United States, residing in Groton, in the county of New London and 5 State of Connecticut, have invented an Improvement in Tags, of which the following description; in connection with the accompanying drawings, is a specification, like reference characters on the drawings representing like parts.

The present invention relates to a tag and is embodied in a tag for marking articles, as for example, in a laundry or cleansing establishment in which goods are to be temporarily marked for identification; so that it is desirable to have the tag firmly held when in use, but easily removed after it has performed its necessary function. The tag embodying the invention consists, as herein- 20 after explained and claimed, of a strip of fabric which can be easily marked, combined with metallic fastening devices by which it is adapted to be fastened to the goods which are to be marked, these fastening devices being permanently secured to and forming part of the tags themselves.

A further feature of the invention consists in a continuous strip of complete tags having the fastening devices secured thereto, the tags being adapted to be cut from the strip when they are to be used. This 30 not only facilitates packing or packaging from the market, but also renders the tags capable of more convenient use in a suitable 35 machine for affixing the tags, it being a simple matter to provide the machine with a cutting device for severing the tags, while the continuous strip is more conveniently fed to a machine than individual tags. Furthermore, when the tags are furnished in 40 this way the fastening prongs by which the tags are to be secured to the goods on which they are to be used, are left unbent, and allowed to project laterally from the sides 45 of the tags so that the entire strip of tags can be rolled up into very little space.

A further feature of the invention is embodied in a peculiar shape of the fastening prongs and the main portion of the blank 50 which results in a neater fit of the tag on the material to which it is attached.

In accordance with the invention, the strip of fabric which constitutes the main or body portion of the tag, is provided at 55 each end with a pair of fastening prongs which project laterally beyond the sides of

the body portion, and are adapted to be turned at a right angle to penetrate the material to which the tags are to be fastened and subsequently clenched on the other side. 60 These fastening prongs are in the form of pointed extensions from the ends of a metal blank which extends across the body portion which is usually a strip of fabric, the said metal blank also having short retaining 65 prongs which are forced through the body portion and clenched. In this way the fastening prongs are permanently fastened to the fabric, but are themselves independent, and need not be bent until the tags are used. 70 As a further, but not essential, feature of the invention, the fastening prongs are slightly bent or curved at the ends, so that when the tags are fastened to an article by 75 clenching the prongs, the points of the prongs will be protected by the material of which the article is made.

Figure 1 is a top plan view of a tag embodying the invention; Fig. 2 is an underneath plan view of the same; Fig. 3 is a 80 plan view of the blank which constitutes the fastening device, shown as it is shaped before it is attached to the material which forms the body portion of the tag; Fig. 4 is a similar view of the blank in the shape 85 to which it is bent in fastening it to the fabric; Fig. 5 is a top view of a strip of tags formed in a continuous piece; Fig. 6 is a perspective view of a single tag showing the fastening devices bent for insertion 90 in the fabric with which the tag is to be used; Fig. 7 is a perspective view of a piece 95 of fabric with one of the tags fastened thereto; and Fig. 8 is a cross section through a tag affixed to an article showing a slight modification in the shape of the fastening device.

Referring to Fig. 1, each tag consists of a body portion 1 of sufficient length to receive any distinguishing mark which may 100 be required; the said body portion, which is commonly a strip of fabric having secured thereto at each end a fastening device consisting of a blank which has a main portion 2 extending substantially across the body portion (hereinafter referred to as the fabric) from one edge thereof to the other, and two projecting fastening prongs 3 which extend beyond the side edges of the fabric. In securing the tag to the article with which it is 105 to be used, the fastening prongs 3 are bent at a right angle to penetrate the material 110

and are then bent parallel to the tag at the other side of the material. As herein shown, these fastening prongs instead of being in a straight line with each other, are to some extent offset, so that when the tag is clenched to the article, the fastening prongs instead of lying one over the other will lie beside each other, thus making the tag less bulky, since there are only two thicknesses of metal 10 instead of three.

A further feature of the invention, as shown in the modification, Fig. 8, consists in slightly bending the ends of the prongs as shown at 3^a, this tending to turn them inward when they penetrate the article to which the tags are to be fastened, and also to force the points into the surface of the article when the prongs are clenched. As shown in Fig. 8, therefore, the ends of the prongs will 15 sink into and be protected by the material of which the article is made, so that they are less likely to be caught and spread apart. In this construction, moreover, if a machine is used for clenching the tags, the clenching die which engages the top of the tag can be 20 made with a slight concavity in the middle, which bends the portion 2 of the fastening device, thus making a slight pocket 2^a to accommodate the inturned points.

30 As shown in Figs. 2, 3 and 4, each of the fastening prongs is provided with short projecting points 4, there being preferably four of such points, one at each corner of the main portion of the blank which extends 35 across the strip of fabric. These points, as shown in Figs. 2 and 4, are forced through the tag strip and clenched over as shown in the underneath plan view, Fig. 2 and in Fig. 4.

40 By this construction, the fastening devices are adequately secured to the fabric portion of the tag; leaving the prongs 3, as shown, entirely out of engagement with the material.

45 A further feature of the invention consists in using a continuous strip of fabric with the fastening devices connected thereto in the proper positions and the fastening prongs left straight and projecting laterally 50 from the side edges of the fabric and in the plane of the fabric, as shown in Figs. 1, 2 and 5.

With this construction a large number of tags can be shipped in a package coiled like 55 a piece of tape, or ribbon.

This construction is very useful if a machine is to be used for affixing and marking the tags automatically; a machine, for example, like one which I have invented and 60 for which I have filed an application Serial No. 34,047, filed June 14, 1915. In a machine of this kind, the tags are bent and affixed, and when the feeding device used is adapted to operate on a continuous strip 65 of fabric, the machine is also provided with

means for cutting the strip into single tags, before they are affixed. Moreover, even if the tags are applied by hand it is no material trouble to cut them from the strip and bend the prongs before inserting them in the article to be tagged while the tags are much less likely to be soiled or damaged than when shaped ready for insertion and packed loose. 70

Fig. 6 shows a perspective view of a single tag with the retaining prongs bent so 75 that the tag is ready to be affixed to another article by forcing the prongs through the material thereof. The fastening is then completed by bending over or clenching the prongs on the other side.

Fig. 7 shows a plan view of a tag affixed to another piece of material and marked.

The construction of the tag is very simple, the small prongs, which are symmetrically arranged at the four corners, being adequate 85 to hold the fastening devices securely in position when the tag is not in use, while the entire fastening device overlies and holds the tag through the agency of the fastening prongs after the tag has been affixed. 90

What I claim is:

1. A tag, consisting of a strip of fabric adapted to receive upon its exposed face a distinguishing mark, and fastening devices arranged on such exposed face near the ends 95 of the tag, each fastening device comprising a main portion extending across the exposed face from side to side and having retaining prongs extending through the fabric and clenched upon its back, and fastening prongs 100 extending laterally beyond the side edges of the fabric and adapted to be bent over such edges backwardly to engage the article to be tagged.

2. A tag, consisting of a strip of fabric 105 adapted to receive upon its exposed face a distinguishing mark, and fastening devices arranged on such exposed face near the ends of the tag, each fastening device comprising a main portion extending across the exposed face from side to side and having four 110 retaining prongs one at each corner of the main portion and extending through the fabric and clenched upon its back, and fastening prongs extending laterally beyond the 115 side edges of the fabric and adapted to be bent over such edges backwardly to engage the article to be tagged.

3. A tag, consisting of a strip of fabric adapted to receive upon its exposed face a 120 distinguishing mark, and fastening devices arranged on such exposed face near the ends of the tag, each fastening device comprising a main portion extending across the exposed face from side to side and having four 125 retaining prongs one at each corner of the main portion and extending through the fabric and clenched upon its back, and fastening prongs extending laterally beyond the 130 side edges of the fabric and beyond said

retaining prongs and curved near their ends and adapted to be bent over such edges backwardly to engage the article to be tagged.

4. Tag construction consisting of a continuous strip of tag fabric, combined with metallic fastening devices secured cross-wise to the exposed face of the strip of fabric and having fastening prongs projecting beyond the edges of said strip of fabric in 10 the plane of the exposed face thereof and adapted to be bent backwardly to engage the article to be tagged.

5. Tag construction consisting of a continuous strip of tag fabric, combined with metallic fastening devices arranged cross-wise upon the exposed face of the strip and having four retaining prongs, one at each corner, passed through the strip and clenched on its back, and also having fastening prongs projecting laterally beyond the 20

edges of said strip in the plane of its exposed face to thereby permit of the convenient packaging of the strip.

6. A tag, consisting of a strip of material having an exposed face which is adapted to 25 be marked, and also having metallic fastening devices applied to its exposed face cross-wise thereof, each of said devices including a main portion provided with a pocket at its middle, retaining prongs engaging the 30 strip, and fastening prongs bent at their outer ends and projecting beyond the opposite sides of the strip of material and adapted when applied to an article to be tagged to be bent toward each other and their bent 35 ends entered into said pocket.

In testimony whereof, I have signed my name to this specification.

CARLTON W. BROWN.
